UNITED STATES PATENT OFFICE.

ABRAHAM OVERHOLT, OF IONIA, MICHIGAN.

CHURN.

SPECIFICATION forming part of Letters Patent No. 248,340, dated October 18, 1881.

Application filed March 10, 1881. (No model.)

To all whom it may concern:

Be it known that I, ABRAHAM OVERHOLT, of Ionia, in the county of Ionia and State of Michigan, have invented certain new and useful Improvements in Churns; and I hereby declare the following to be a full, clear, and exact description thereof, which will enable others skilled in the art to which my invention relates to make and use the same, reference being had to the accompanying drawings, forming a part hereof, and in which—

Figure 1 represents a vertical longitudinal section, and Fig. 2 an end view of the same, showing the gearing and exterior mechanism. Fig. 3 represents a vertical longitudinal section of the bearing *f*, cut on the line *xx*; and Fig. 4 represents a front view of the same.

Like letters of reference indicate like parts.

In the drawings, *A* represents a frame or horse, constructed of any suitable material and dimensions, and upon which are mounted at the farther end a bearing, *h*, carrying the pin *g*, fastened to the center of the head of the churn, and at the other or near end the open or semicircular bearing *f*, in which rests and revolves one end of the shaft *C*, passing loosely through the center of the near head of the churn, and which is provided with a pinion, *d*. The other end of said shaft is provided with a bearing, *h'*, upon the inner side of the farther head of the churn at its center, and upon said shaft *C* and pin *g*, arranged, as shown, upon the bearings *f* and *h*, rests and revolves the churn *B*.

Over the outer end of the shaft *C* and pinion *d*, and gearing therewith, turns an inside geared cog-wheel, *e*, upon a stud, *i*, fastened to the near head of the churn at an angle of about forty-five degrees from the center line, connecting the shaft *C* and funnel-shaped opening *l* of the churn. Through the outer end of the stud *i* passes a pin, *i'*, which holds said wheel *e* upon it, and the rim upon the outer end of its teeth holds the pinion in its place.

A pin, *k*, passing through the frame *A* into the head of the churn, holds it firmly in the desired upright position in the frame. Within the churn *B*, upon the shaft *C*, and so as to revolve therewith, are mounted paddles or dashers *C'*, of any desired form.

The operation of my improved churn is as follows, to wit: The churn is mounted with its opening *l* uppermost upon the horse by passing the pin *g* through the bearing *h* and laying the end of the shaft *C*—previously inserted into the churn—upon the bearing *f*. The pin *k* is then passed through the frame into the churn, as shown, to hold it in its desired position, after which the wheel *e* is mounted upon its stud *i* and over the pinion *d*, and fastened, as shown, and motion given to the shaft *C* and its attached paddles by turning the wheel *e*.

When it is desired to empty the churn the pin *k* is withdrawn and the churn turned forward on its bearings, so that the opening *l* may be under the vertical center thereof before the stud *i* strikes against the horse *A*.

Having thus described my invention, what I claim as new, and desire to secure by Letters Patent, is—

A churn provided with a loosely-revolving shaft, *C*, longitudinally removable through its head, and provided with paddles and a bearing, *h'*, in the center of the inside end of the churn, and bearing *f'* through the head, in combination with stud *i* and opening *l*, located at such angle therewith as to be vertically under the shaft *C* when the churn is inverted, and the stud *i* strikes the horse *A*, horse *A*, stud *g*, bearings *h* and *f*, inside geared wheel *e*, pinion *d*, and pin *k*, all constructed and combined to operate substantially as and for the purpose specified.

ABRAHAM OVERHOLT.
